Primary Examiner — Brett Miller(74) *Attorney, Agent, or Firm* — Cook Alex Ltd.; R. Blake Johnston(57) **CLAIM**

The ornamental design for a partition system, as shown and described.

DESCRIPTION

FIG. 1 is a perspective view of a first embodiment of the partition system;

FIG. 2 is a front elevation view of the first embodiment of the partition system;

FIG. 3 is a rear elevation view of the first embodiment of the partition system;

FIG. 4 is a left side elevation view of the first embodiment of the partition system;

FIG. 5 is a right side elevation view of the first embodiment of the partition system;

FIG. 6 is a top plan view of the first embodiment of the partition system;

FIG. 7 is a bottom plan view of the first embodiment of the partition system;

FIG. 8 is a perspective view of a second embodiment of the partition system;

FIG. 9 is a front elevation view of the second embodiment of the partition system;

FIG. 10 is a rear elevation view of the second embodiment of the partition system;

FIG. 11 is a left side elevation view of the second embodiment of the partition system;

FIG. 12 is a right side elevation view of the second embodiment of the partition system;

FIG. 13 is a top plan view of the second embodiment of the partition system; and,

FIG. 14 is a bottom plan view of the second embodiment of the partition system.
